ENVELOPE OPENING DEVICE

Frederick A. Kelsall, Boulder, Colo.

Application April 23, 1945, Serial No. 589,869

3 Claims. (Cl. 30—131)

1

My invention relates to improvements in envelope opening devices, the primary object in view being to provide a device of simple, inexpensive construction for shearing one edge of an envelope quickly and evenly so that the contents may be quickly removed, and which functions to shear the edge off uniformly in predetermined degree, store the cuttings in hidden condition for subsequent disposal thereof, is self-sharpening, easy to operate, will not get out of order, and is adapted for prolonged use.

To the accomplishment of the above, and subordinate objects presently appearing, a preferred embodiment of my invention has been illustrated in the accompanying drawings, set forth in detail in the succeeding description, and defined in the claims appended hereto.

In said drawings:

Figure 1 is a view in top plan of my improved envelope opening device, in its preferred embodiment,

Figure 2 is a view in front elevation,

Figure 3 is a view in longitudinal section taken on the line 3—3 of Figure 1,

Figure 4 is a view in perspective with parts shown in section,

Figure 5 is a view in end elevation partly in section.

Figure 6 is a view in transverse section showing a modification of the invention.

Referring to the drawings by numerals, my improved envelope opening device, as shown, comprises an elongated, rectangular casing 1 of substantially the length of the usual letter envelope and which is provided with front, rear, bottom, top and end walls designated 2, 3, 4, 5 and 6, respectively. Preferably, the corners of the casing 1 are beveled, as at 7, to obviate sharp edges. One end wall 6 is provided with a circular outlet opening 8 therein closed by a threaded disc-type closure 9 having a knurled edge 10 providing for a firm grip thereon. A longitudinal, central slot 11 is provided in the front wall 2 and end walls 6, said slot 11 opening into the casing 1 between the end walls 6 and being of the requisite width to accommodate therein one edge of the usual letter envelope, as shown in dotted lines at 12. Beveled guide ribs 13 are provided along the top and bottom of said slot 11 to facilitate entering the edge of the envelope 12 in said slot.

A stationary, bar-like shearing blade 14, of rectangular cross section, extends along the bottom of the slot 11, inside the casing 1, from end to end of the casing and with an upper flat shearing edge 15 level with the bottom of the slot 11, said blade

2

being secured to the front wall 2, as by screws 16, with a spacing means between the blade and said wall. Preferably, the spacing means has the form of a spacing bar 17 of the same type as said blade 14 and which is secured in place by said screws 16. The shearing blade 14 may be provided with widened ends, as at 18, bearing against the bottom wall 4 to align the edge 15 with the bottom of the slot 11.

10 A vertically rocking shearing blade 19, similar to the blade 14, but having a right angled down-turned end 20, is pivoted to one end and rear side of said blade 14 by a screw 21 passing through said end 20 into the blade 14, and whereby a lower shearing edge 22 on said blade 19 is arranged to coact with the shearing edge 15 of the blade 14 when the blade 19 is rocked downwardly against the edge of the envelope 12 inserted between said blades. A relatively wider stop plate 23 extends 15 along the back of the shearing blade 19 in overlapping relation to said shearing blade 14 and which is secured to the shearing blade 19, as by screws 24. At the end of the shearing blade 19 opposite the pivot screw 21, the stop plate 23 is 20 provided with an upper edge extension 25 projecting out of the casing 1 through a top slot 26 in the wall 5, said extension being provided with a right angled edge flange 27 overlying the top wall 5 and forming a pressure member for rocking 25 the shearing blade 19 and the stop plate 23 downwardly. A coil spring 28 interposed between the top wall 5 and said flange 27 and countersunk at its ends in said top wall and flange yieldingly holds the flange 27 elevated and consequently the 30 shearing blade 19 and stop plate 23 in elevated normal position in which an edge of the envelope 12 may be inserted between said shearing blades 14 and 19.

35 The casing 1 and closure 9 may be formed of any light strong material, preferably a plastic. The shearing blades 14 and 19, together with the spacing bar 17 and the stop plate 23, are preferably formed of metal.

40 The manner in which the described invention is used and operated will be readily understood. With the casing 1 grasped, for instance, in the left hand, the selected edge of the envelope 12 is inserted in the slot 11 against the stop plate 23 and the shearing blade 19 is then rocked downwardly 45 by pressure exerted, for instance, by the thumb, on the flange 27. The shearing blade 19 is thus caused to cooperate with the shearing blade 14 to shear off said edge of the envelope 12, the cuttings falling between the shearing blade 14 and 50 the stop plate 23 into the bottom of the casing. 55

The coil spring 28 opposes depression of the flange 27 and the described operation of the shearing blade 19 and stop plate 23 and, as shown in Figure 4, limits downward movement of these parts so that excessive operation of the shearing blade 19 is prevented. As will be clear, the spring 28 returns the operated parts to the described normal condition. The stop plate 23, it will be seen, provides a gauge for predetermining the width of the cutting which is sheared off the edge of the envelope 12. As shown in Figure 6, a spacing bar 29 similar to the shearing blade 19 may be interposed between said blade 19 and the stop plate 23, and the stop plate 23 may be set back further from the slot 11 to provide for a wider cutting being sheared from the envelope 12. It may be stated at this point that the slot 26 is wider than the extension 23 so as to provide for such setting back of the stop plate 23. Since the slot 11 extends from end to end of the casing 1, as previously described, envelopes longer than the casing 1 may be slid into said slot from the appropriate end of the casing 1 and the edge of the envelopes sheared off progressively. Accumulated cuttings may be disposed of by unscrewing the closure 9 and removing said cuttings through the opening 8.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In an envelope opening device, an elongated substantially rectangular casing adapted to form a closed storage receptacle for envelope cuttings and embodying a front side and a top, said side having a longitudinal slot therein for insertion of one edge of an envelope therethrough into said chamber, a shearing blade in said chamber fixed to said side and having an upper shearing edge extending along the bottom of said slot, a second shearing blade in said chamber pivoted at one end of the fixed blade for rocking movement from normal position into cooperative relation to the fixed blade to cut said edge of the envelope with a shearing action, an edge extension on the other end of said pivoted blade extending through said top and provided with a lateral flange forming a presser member for rocking said pivoted

blade, and a spring interposed between said top and said flange and thereby yieldingly retaining said pivoted blade in raised position.

5 2. In an envelope cutting device, an elongated substantially rectangular casing adapted to form a closed storage receptacle for envelope cuttings and embodying a front side and a top, said side having a longitudinal slot therein for insertion of one edge of an envelope therethrough into said chamber, a shearing blade in said chamber fixed to said side and having an upper shearing edge extending along the bottom of said slot, a second shearing blade in said chamber pivoted at one end to one end of the fixed blade for rocking movement from normal position into cooperative relation to the fixed blade to cut said edge of the envelope with a shearing action, an edge extension on the other end of said pivoted blade extending through said top and provided with a lateral flange forming a presser member for rocking said pivoted blade, a spring interposed between said top and said flange and thereby yieldingly retaining said pivoted blade in raised position, and a stop bar fixed on said pivoted blade to establish the position of said edge of the envelope relative to said blades.

3. In an envelope opening device, an elongated substantially rectangular casing adapted to form a closed storage receptacle for envelope cuttings and embodying a front side and a top, said side having a longitudinal slot therein for insertion of one edge of an envelope therethrough into said chamber, a shearing blade in said chamber fixed to said side and having an upper shearing edge extending along the bottom of said slot, a second shearing blade in said chamber pivoted at one end to one end of the fixed blade for rocking movement from normal position into cooperative relation to the fixed blade to cut said edge of the envelope with a shearing action, an edge extension on the other end of said pivoted blade extending through said top and provided with a lateral flange forming a presser member for rocking said pivoted blade, a spring interposed between said top and said flange and thereby yieldingly retaining said pivoted blade in raised position, a stop bar fixed on said pivoted blade to establish the position of said edge of the envelope relative to said blades, and spacing means between said fixed blade and said side of the casing for setting said blades back from said slot.

FREDERICK A. KELSALL.
